COAL CUTTER AND LIKE MACHINERY

Harold Wilson, Bestwood, England

Application November 29, 1933, Serial No. 700,293
In Great Britain November 30, 1932

13 Claims. (Cl. 262—30)

This invention is concerned with that kind of machine which is known as a coal cutter and is employed both for cutting coal and for cutting other minerals, and the invention is applicable to all types of coal cutters, either chain, bar or disc. In use the coal cutter is traversed along the coal face and by means of a cutting element (which is either a chain travelling round a jib, or a rotating disc, or a rotating and reciprocating bar) makes an undercut in the face, and hitherto it has been necessary to employ men at the rear of the machine to clear out the cuttings from the cutter as they are made. There is a danger however of the men thus occupied being caught in the cutting element, and the present invention has for its chief object to provide means for clearing out the cuttings and for guarding the cutting element, and for thereby reducing not only the number of men that must be in attendance upon the machine but also, by obviating the necessity for clearing out the cuttings by human labour, reducing the risk of accidents. A further object of this invention is to provide a guard for the cutter which does not compact the cuttings as the machine is traversed.

In order that the invention may be better understood, two embodiments thereof will now be described in detail with reference to the accompanying drawings in which

30 Figure 1 is a plan view of a chain cutter according to this invention.

Figure 2A is an elevation, upon an enlarged scale, looking in the direction of the arrow 2a in Figure 1, while

35 Figure 2B is, in effect, a continuation to the left of Figure 2A, and shows an elevation of the machine looking in the direction of the arrow 2b in Figure 1.

Figure 3 is a sectional elevation, upon an enlarged scale, taken on the line 3—3 of Figure 1.

Figure 4 is a further sectional elevation taken on the line 4—4 in Figure 1.

Figure 5 is a part-sectional plan of the head-stock for the jib, showing a support for a rotary guard shaft according to this invention.

Figure 6 is an inverted plan of a pivotal support for a cleaner bar or plough according to this invention.

50 Figure 7 is a section through the guard shaft adjacent to the jib.

Figure 8 is a section through said shaft adjacent to the head-stock, while

55 Figure 9 is a plan view of a disc cutter according to this invention.

Throughout this description like reference numerals indicate like parts.

The mining machine shown in Figure 1 follows conventional lines in that it comprises a body 10 and a jib 11 pivoted thereto at 12, round the periphery of which jib a cutter chain is traversed, said chain having projecting cutters 13. The details of this chain form no part of this invention and are, therefore, not illustrated; neither do the means whereby said chain is traversed, in an anti-clockwise direction as viewed in Figure 1, nor the means whereby the whole machine is traversed along the working face, in the direction of the dotted arrow in Figure 1, whereby the cutter mechanism consisting of the jib, 10 chain, etc., cuts a deep undercut in the working face. It will suffice to say that a motor is housed in the body 10 which drives the chain through suitable gearing and also causes the machine to traverse by reason of a driven capstan 14 around 15 which the wire haulage rope 15 that extends to the derrick prop is wound. This capstan 14 in some machines is rotated intermittently to give a step by step traverse and in other machines is rotated continuously to give a substantially 20 smooth traverse.

According to this invention, the cutters at the trailing side of the jib are guarded by a guard shaft or bar 16 that extends along one lap of the cutter chain. This guard bar 16 is approximately of the same diameter as the thickness of the jib and height of the undercut, that is to say if the machine has a 5" jib, the bar 16 will preferably be some 4½" in diameter. The function of this bar is to prevent the tools, which the 30 machine attendants employ to clear out the cuttings, from being caught in the cutters.

It is desirable that means shall be provided whereby, as the machine is racked along the coal face, the cuttings are passed to the rear side of 40 said guard shaft 16 without being compacted or pressed down by the passage of said guard over them. Therefore to this end the shaft 16 is rotatable, being supported in ball or roller bearings in housings 17, 18 upon the jib head-stock, 45 and has its periphery cut with axially extending flutes 19 or deep grooves forming between them radially projecting vanes or blades 20. Hence, as the machine is drawn forward the vanes 20, by reason of the rotation of the shaft 16, step over 50 the cuttings, which are accommodated in the flutes 19 and are not compacted. From this it will be appreciated that it is preferred that the shaft 16 shall be rotated in co-relation with the traverse or racking movement of the machine 55

itself, that is to say the peripheral speed of the shaft 16 shall be substantially the same as the linear speed of the machine. When the machine is racked intermittently, it is preferred that the shaft 16 shall be rotated intermittently, the rotational movement coinciding with the racking movement.

The shaft 16 is driven by suitable gearing from the hereinbefore mentioned motor that is housed 10 within the body 10; by way of example in the construction illustrated the haulage rope 15 is employed to rotate said shaft 16. It will be seen that the said rope extends from the derrick prop back to the machine body 10, over an idle 15 roller 21 on the face side of the machine, over an idle roller 22 at the goaf side of the machine, and then alongside the machine body to a pulley 23 that is supported upon said body at the head-stock end thereof. The haulage rope passes over 20 said pulley 23 and back over another idle pulley 24 that is co-axial with the aforesaid pulley 22 and thence to the winding up capstan or drum 14. Therefore as the haulage cable is wound 25 up on the drum 14 the pulley 23 is rotated upon its supporting shaft 25 (which shaft is mounted upon the machine in a manner hereinafter explained) as is also a sprocket 26 which is attached to said pulley. This sprocket wheel 26 serves by means of a chain 27 to drive a corresponding sprocket 28 at the head-stock end of 30 the guard shaft 16, which shaft is thereby rotated in an anti-clockwise direction as viewed in Figure 2A.

According to a further feature of this invention means are provided for delivering, out of the cut being made, the cuttings that are produced by the cutters 13. The said means comprises a bar or plough 30 that extends backwardly and obliquely from the extremity of the 35 guard shaft 16, conveniently at an angle of some 30° thereto, so that as the machine is traversed the cuttings that pass to the rear of the guard 40 shaft 16 are engaged by the plough 30 and are delivered out of the cut. It will be noted that the said plough 30 is of a length at least equal to the 45 effective length of the jib, and, therefore, at least equal to the greatest depth of undercut. This ensures that the cuttings are delivered out beyond the coal face.

Because of the movement of the cutters 13 around the peripheral edge of the jib, it is not possible to support the plough 30 directly from the jib, and it is convenient, therefore, to mount the said plough rotatably upon the extremity 50 16a of the guard shaft 16. This rotatable mounting has the further advantage that it permits the plough to swing in a vertical direction as it trails behind the jib and, therefore, to accommodate itself to such deviations from the true horizontal or straight traverse that may be imposed upon the machine by the configuration 55 of the seam being worked.

In the majority of cases, it will not be practicable to depend solely upon the pivotal mounting on the shaft 16 for supporting the plough 60 30 and, therefore, a stay or tie rod 32 is with advantage provided, which rod extends between the outer end of said plough and the head-stock end of the machine body. In order to permit of the aforesaid swinging movements 65 of the plough 30 the said tie rod is pivoted to the body and to the plough. That is to say at its end near the head-stock the tie rod 32 is forked to span a vertical pin 33 to which the said 70 fork is pivoted by a bolt 34, while at its other 75

end the tie rod 32 is pivoted to the plough 30 by a substantially horizontal pivot 35. It will be noted that the pin 33 is accommodated within one of the holes 36 which are provided, as is common practice, for fastening the jib in the required position of angular adjustment with relation to the body 10.

Because the jib 11 may be moved pivotally to project from one side or the other of the body 10 in accordance with the conditions under which the machine has to be worked and traversed, it is desirable to provide means for transferring the guard shaft 16 and plough 30 to the other side of the jib from that shown in Figure 1. Therefore the bearing housings 10 17, 18 for the shaft 16, and the spindle 25 on which the pulley 23 and sprocket 26 are mounted, are made detachable so that the two said housings may be transferred to the other side of the head-stock and the spindle 25 to the 15 other side of the body.

Referring to Figure 3, it will be noted that the spindle 25 is secured by means of a set screw 38 within a bracket 39, which bracket is provided upon its underside with a vertical stub-shaft 40. This stub-shaft 40 may be engaged within one or other of the locating holes 36a which, as is usual in chain cutters and as is shown in Figure 1, are provided at substantially diametrically opposed points in the head-stock 30 end of the body. The said stub-shaft 40 is prevented from turning within its hole 36a because one or other (according to which side of the body the bracket 39 is located) of the projecting arms 39a is held against the flat faces, indicated at 10a, upon the machine body by reason of the tension in the two laps of the haulage rope that extend alongside the body and over the pulley 23.

In order to provide for the reversible attachment of the two bearing housings 17, 18 for the guard shaft 16, the head-stock 41 and what may be termed the head-stock cap 42 (by means of which head-stock and cap the jib 11 is pivotally mounted upon a stout vertical shaft 43 secured within the overhanging end of the body 10) are of modified design. The housing 18 is supported by means of a curved bracket 44 that may be bolted to either of two lateral extensions 46 of the head-stock, which extensions are suitably tapped at right angles to the length of the jib to receive the securing bolts 45. The other housing 17, as is best shown in Figure 5, is bolted to a distance piece 48 which has at one end a socket within which one or 55 other of two cylindrical extensions 149, integral with a stout arm 150 that projects from the head-stock cap 42, is received.

The guard shaft 16 is assembled within its bearings in the housings 17, 18 by endwise movement. Therefore, that portion 16b of said shaft 16 that lies between the two bearings must be reduced in section, to pass through said bearings, and a removable distance piece provided. This distance piece 48, which is shown in section 65 in Figure 5, is split diametrically into two halves which are bolted upon the shaft 16b by means of flanges 49 and bolts 50. Provision is made, however, for preventing the distance piece 48 by reason of its diameter from fouling the projections or cuttings upon the floor or other support over which the machine is traversed, and therefore this distance piece, like the guard shaft 16, is formed with flutes and projecting vanes or blades. Further in order to ensure that the 70 75

blades that lie between the two bearings are always in alignment with the blades 20 formed on that part of the shaft 16 that lies alongside the rear edge of the jib the distance piece is 5 keyed to the shaft 16. Conveniently, the necessary keyed connection is provided by squaring the portion 16b of the shaft 16. For convenience, this distance piece is not shown in Figures 1, 4, 5 and 9.

10 The present invention is not limited in its application to chain cutters and, therefore, it has been elected to illustrate in Figure 9 the application of the invention to a disc cutter. This disc cutter is in the main of conventional construction comprising a body 10 having projecting brackets 51 between which the horizontal disc 52, provided at its peripheral edge with cutters 13, is pivotally mounted. As in the machine illustrated in Figure 1, the cutters 13 are driven 15 and the machine is traversed by means of a motor housed within the body 10; in particular the body 10 comprises three separable units 10A, B and C, of which the unit 10A comprises a gear box from which there projects a driving shaft 53 having 20 a pinion 54 mounted thereon. This pinion drives the cutter disc 52. At the trailing edge of the cutter disc there is a fluted guard shaft 16 which as before is supported in bearings in 25 housings 17, 18 and also carries a pivotally mounted plough 38, the outer end of which is stayed by a stay rod 32. The general details of 30 this cutter guard 16 and plough 38 are as hereinbefore described and further description of them is unnecessary with the following exception.

35 In the construction shown in Figure 9, the guard bar 16 is provided near the inner bearing housing 18 with a sprocket 56 over which runs a chain 57 that is driven by a small sprocket 58a upon a shaft projecting from the gear box 10A. At the other end of the said gear box 40 there is a similar sprocket 58b which is driven in an opposite direction to the sprocket 58a and is employed to drive the guard bar 16 in the reverse direction when the latter has been 45 changed over to the other end of the body as said guard may be, in order to bring it to the trailing edge of the disc, when it is desired to reverse the cutting traverse of the machine. This reversal of the guard is conveniently effected in 50 substantially the same manner as in the machine shown in Figure 1; that is to say by changing over the bearing housings 17, 18, to the other end of the body 10. As is well known in mining machines, the machine illustrated is arranged 55 for traverse with the cable drum at either the leading or trailing end of the body.

1. In a coal-cutter or mining machine of the type comprising a body and a cutting element projecting therefrom in such manner that as the body is traversed along a working face the projecting cutting element makes a deep undercut in said face, a rotatable fluted guard that extends alongside the trailing edge of the cutting element for substantially the full length thereof, means 60 for rotating said guard, and a device that extends from near the extremity of the cutting element for discharging the cuttings out of the cut by reason of and during the traverse of the machine.

2. In a mining machine of the type adapted to 65 be traversed along the working face to cut a deep undercut therein by means of an overhanging cutter having movable cutter elements thereon which travel in an endless path in a plane which lies substantially in the direction of traverse, the 70 combination of a rotatable guard bar extending

alongside the trailing edge of the cutter for substantially the full length thereof and having a fluted periphery, and means for rotating said guard bar.

3. In a mining machine of the type adapted to be traversed along the working face to cut a deep undercut therein by means of an overhanging cutter having movable cutter elements thereon which travel in an endless path in a plane which lies substantially in the direction of traverse, 10 the combination of a rotatable guard that extends alongside the rear edge of the cutter and has radial blades, means for rotating said guard, and a plough, extending obliquely to the direction of traverse of the machine from the extremity of 15 the cutter, for delivering the cuttings out of the cut.

4. In a mining machine of the type adapted to be traversed along the working face to cut a deep undercut therein by means of an overhanging cutter having movable cutter elements thereon which travel in an endless path in a plane which lies substantially in the direction of traverse, 20 the combination of a rotatable guard having a fluted periphery which guard extends alongside the cutter at the rear thereof, a plough for delivering cuttings out of the cut as the machine is traversed, means for rotatably supporting said plough at 25 the extremity of the guard, and means for rotating 30 said guard.

5. In a mining machine comprising a body and an overhanging horizontal cutter disc for making an undercut in a working face as the machine is traversed along said face, the combination of a 35 rotary guard bar extending from the body substantially tangentially of the disc at the trailing edge thereof, said guard bar having an interrupted periphery for permitting it to move over the cuttings without compacting them, and a plough trailing behind said guard bar for 40 delivering the cuttings out of the cut.

6. In a mining machine comprising a body and an overhanging horizontal cutter disc for making an undercut in a working face as the machine is traversed along said face, the combination of a 45 guard that extends from the body at the trailing edge of the disc, means for causing said guard to pass over cuttings made by the disc without compacting them as the machine is traversed, and means for delivering the cuttings out of the cut 50 during traverse.

7. In a mining machine comprising a body and an overhanging cutter projecting therefrom by means of which cutter a deep undercut is made 55 in a working face of mineral as the machine is traversed along said face, the combination of a guard that extends alongside the trailing edge of the cutter and in the same horizontal plane and is of substantially the same thickness as the under-cut, means for causing the cuttings made 60 by the cutter to pass uncompacted to the rear of the guard as the machine is traversed, and means for delivering the cuttings out of the cut during traverse.

8. In a machine of the type comprising a body, 65 a jib projecting horizontally therefrom, a cutter chain guided around the periphery of the jib, cutters upon said chain, and an engine in the body for driving the chain and for providing the power for traversing the machine, so that upon traverse 70 of said machine along a working face a deep undercut is made therein, the combination of a rotary guard bar of substantially the same diameter as the thickness of the jib extending alongside 75 the trailing edge of the jib which guard bar has

- an interrupted periphery for permitting it to step in its rotational and traversing movement over the cuttings without compacting the same, means for rotating said guard bar at a peripheral speed substantially equal to the linear speed of traverse of the machine, a bearing for said guard bar to support it, and a trailing plough pivotally mounted upon the extreme end of the guard bar for delivering the cuttings out of the cut.
10. 9. In the combination claimed in claim 8, alternative mountings for said bearing, one at each side of the jib, and means for attaching the bearing to either of them at will, whereby the guard may be located alongside either edge of the jib according to the direction of traverse of the machine.
10. 10. In a coal-cutter or mining machine of the type adapted to be traversed along the working face to cut a deep undercut therein by means of an overhanging cutter having movable cutter elements thereon which travel in an endless path in a plane lying substantially in the direction of traverse, the combination of a guard that extends into the cut alongside the trailing edge of the cutter and is of substantially the same vertical height as the undercut, a trailing plough for engaging the cuttings and delivering them by a ploughing action out of the cut being made, and means for pivotally mounting said plough for free up and down swinging movement in the rear of the guard.
11. In a mining machine of the type having a

jib and a cutter chain therefor running round the periphery of the jib, a rotatable cutter guard of non-circular section extending alongside the trailing lap of the chain, bearings in which said guard is rotatable, means for rotating it to step forward over the cuttings, and means for delivering the cuttings out of the cut during traverse of the machine.

12. In a mining machine of the type comprising a body and overhanging cutter mechanism projecting therefrom, said mechanism comprising cutters or picks that travel in an endless path in a substantially horizontal plane as the machine is traversed along the working face to make a deep undercut in said face, the combination of a 15 rotatable cutter guard of non-circular section extending alongside the trailing edge of said mechanism, bearings in which said guard is rotatable, the transverse dimension of which guard on a longitudinal section through the axis of rotation 20 is substantially equal to the depth of undercut and on a further such section is less than the depth of undercut, means for rotating said guard in synchronism with the traverse of the machine and for thereby causing it to step forward over 25 the cuttings, and means at the rear of the guard for delivering the cuttings out of the cut.

13. In the combination claimed in claim 12, a motor in the body of the machine for traversing said machine, and a driving connection between said motor and the guard for rotating it

HAROLD WILSON.
